UNITED STATES PATENT OFFICE.

JOHN M. DRAKE, OF WEST HARTFORD, CONNECTICUT.

GRINDSTONE ATTACHMENT.

No. 828,971.

Specification of Letters Patent.

Patented May 26, 1908.

Application filed December 11, 1907. Serial No. 406,071.

To all whom it may concern:

Be it known that I, JOHN M. DRAKE, a subject of the King of Great Britain, residing at West Hartford, in the county of Hartford and State of Connecticut, have invented new and useful Improvements in Grindstone Attachments, of which the following is a specification.

This invention relates to grindstone attachments, and particularly to an attachment whereby bush hammer blades, chisels, plain blades of various kinds and edged tools may be held in a convenient manner to be ground and adjusted laterally and vertically with respect to the stone, as occasion may require in the grinding operation, and whereby power may be applied to force the blade with a heavy pressure against the stone, thereby enabling thick blades to be readily and evenly ground.

The object of the invention is to provide a device of this character which may be conveniently applied to any ordinary grindstone frame, which may be quickly removed when its use is not desired, which may be produced at a comparatively low cost, and which will save time and labor in shops where heavy blades or a large number of blades are constantly being sharpened.

The invention consists of the features of construction, combination and arrangement of parts hereinafter described and claimed, reference being had to the accompanying drawing, in which:—

Figure 1 is a side elevation of a grindstone having my attachment applied thereto. Fig. 2 is a sectional end elevation thereof. Fig. 3 is a side view of the work holder or tongs detached. Fig. 4 is a plan view of the same. Fig. 5 is a view showing a modification.

Referring to the drawing, the numeral 1 designates the frame of an ordinary grindstone, upon which the stone 2 is revolvably mounted, which stone may be operated by hand, foot or other power.

The attachment is mounted in practice upon one end of the frame 1 and comprises a supporting frame in the form of a pair of brackets 3 preferably of U-form to encompass, bear and rest upon the upper and lower surfaces and outer sides of the upper longitudinal bars of said frame 1, the lower arms of said brackets being inwardly extended and bent downwardly to provide apertured ears 4 connected by a bolt or other suitable fas-

tening 5. From the upper arms of the U-shaped brackets extend vertical parallel standards 6, each provided with a series of transverse openings 7, the openings in the standards being arranged in alinement with each other.

The standards are connected by a transverse tie rod or bolt 8 passing through one of the series of openings in each standard, one end of the bolt being headed to bear against the outer surface of one standard, while the other end of the bolt is threaded, as at 9, to receive a clamping nut 10, by which the bolt is secured from disconnection and the standards rigidly tied together. It will thus be seen that the upper and lower bolts detachably secure the parts of the frame of the work holder firmly in position upon the frame of the grindstone, and that the construction of the work holder is such as to adapt it to be applied to any ordinary form of grindstone frame and to be conveniently removed therefrom when occasion requires. As shown in Fig. 5, the ear 4 on each bracket may be dispensed with and the bracket secured to the frame by a set-screw 5a.

A clamp or work holder is pivotally and slidably mounted upon the bolt 8, which forms a supporting arbor therefor, and in the form shown embodies a pair of tongs or clamping members 11 and 12 which are crossed in the customary manner adjacent their forward ends and pivotally connected, as at 13, and provided with coöperating clamping jaws 14 and 15. The rear ends of the tongs form the usual operating handles 16 and 17, which may be of any desired length for application of the required amount of clamping power. The member 12 is provided at a point below the pivot 13 with an apertured lug or ear 18 which depends therefrom and slidably and pivotally engages the arbor 8, thus enabling the work holder, between the jaws 14 and 15 of which the article to be sharpened is held, to be adjusted laterally and vertically with respect to the face of the stone 2 to enable the article to be manipulated and ground with facility.

It will be understood by the construction described that the arbor or pivot bolt 8 may be mounted at different elevations upon the work holder frame by passing it through different alined openings 7 in the standards 6, thus providing for the adjustment of the tongs to hold objects to be sharpened which vary in length or thickness. The article to

be sharpened is clamped between the jaws 14 and 15 by drawing the handles 16 and 17 together, and through the medium of the latter a firm and effective clamping action 5 may be obtained. By pivotally and slidably mounting the tongs upon the arbor, the article may not only be adjusted laterally and vertically in the manner before described, but a high forcing pressure or leverage may 10 be exerted by upward pressure on the handles of the tongs to hold the article with maximum force against the face of the wheel, thereby enabling thick and heavy edged tools to be sharpened with convenience.

15 From the foregoing description, taken in connection with the accompanying drawing, the construction, mode of operation and advantages of my improved attachment will be readily understood, and it will be apparent 20 that by its use a material amount of time and labor may be saved in the operation of sharpening heavy tools and a large number of tools at more or less frequent intervals.

Having thus fully described the invention, 25 what is claimed as new is:

1. A work holding attachment for grindstones comprising a supporting frame, and a work holder embodying clamping jaws having operating handles, one of said jaws being 30 pivotally and slidably mounted on said frame for adjustment respectively toward and from the stone and laterally of the face thereof, and the other jaw being pivotally mounted

upon the first-named jaw and bodily adjustable therewith.

2. A work holding attachment for grindstones comprising a supporting frame, and a work holder comprising a pair of pivotally connected jaws, one of said jaws being slidably and pivotally mounted upon the frame 40 for adjustment toward and from the stone and laterally of the face thereof, and handles connected with the jaws for the manual manipulation thereof.

3. In a work holding attachment for grindstones, the combination of a frame having a grindstone journaled thereon, standards carried by the frame on opposite sides of the line of the grindstone, a transverse rod carried by said standards, said rods being adjustable 50 vertically on the standards to different operative positions, and a work holder pivotally mounted on said rod for adjustment toward and from the stone and slidably mounted on the rod for movement laterally of the face of 55 the stone, said holder comprising a pair of pivotally connected jaws, one of said jaws being slidably and pivotally mounted on the rod, and both of said jaws being provided with handles for manual manipulation.

In testimony whereof I affix my signature in presence of two witnesses.

JOHN M. DRAKE.
